WINDOW

Spiro Prifti, Chicago, Ill.

Application May 2, 1935, Serial No. 19,436

7 Claims. (Cl. 20—43)

The invention relates to windows of the combined sliding and swinging type whereby the cleaning of windows is facilitated and rendered extremely safe. It is an object of the invention 5 to provide means for swinging the sashes about axes coinciding with the lower member of each sash and in alignment with the chains supporting the sashes.

A further object aims at providing stationary 10 bearing members constituting pivots for the window sashes so that the latter may be swung inwardly at predetermined portions.

A still further object aims at permitting the 15 lower sash to be swung inwardly to a variable degree so that the lower sash at any position between the vertical and horizontal positions acts as a ventilator.

A still further object aims at providing guiding 20 means for the sashes, weather strips and other features tending to enhance the utility and efficiency of windows of the swinging type.

With these and other equally important objects in view, which will appear from a perusal 25 of the invention, the latter comprises the means described in the following specification, particularly pointed out in the claims forming a part thereof, and illustrated in the accompanying drawings, in which:

Fig. 1 is a perspective view of a window frame 30 and its sashes constructed in accordance with my invention.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is a section on the line 5—5 of Fig. 1.

Fig. 6 is a perspective view of a bearing member for the upper sash.

Fig. 7 is a perspective view of a bearing member for the lower sash, and

Fig. 8 is a perspective view of a bolt.

The window comprises the usual frame member 10, in which the upper and lower sash 11 and 12 respectively are provided for vertical movement and are supported by the customary 45 chains or cords which are trained around sheaves and have secured thereto sash weights. In describing the present invention, only those parts are specifically referred to which are necessary for an understanding of the improvements on 50 which the invention is predicated.

The lower window sash 12 is provided near the bottom and at either end with a bracket 14 (Fig. 5) which has a projection 15 riding in a vertical slot 16.

55 Secured to the window frame 10 and in align-

ment with the slot 16 is a bearing member 17 of angular form (Fig. 7) comprising a face plate 18 having a plurality of holes 19 to receive screws permitting the bearing member 17 to be secured in a rabbet of the window frame 10. The face 5 18 extends into a flange 20 at right angles thereto and provided with a horizontal lug 21 formed with an aperture 22. The face plate has a large opening 23 leading to a vertical slot 24 terminating at the upper end of the plate.

A vertical rod 25 extends through the aperture 21 and is held at the upper end by a clip 26 (Fig. 2). The rod is encircled at the upper end by a coiled spring 27 bearing at one end against said clip and with the other end against a blade 28. 15 There are two bearing members, one at each side of the sash and two blades 28 which serve as a sealing means for the window.

In the normal position of the lower sash, the projection 15 is in the large opening 23 of the bearing member 17. When the sash is to be raised the projection 15 will be guided along the slot 16 and the blades 28 hold it in upright position.

As will be seen from Fig. 1, spring controlled 25 bolts 30 are mounted on top of the lower sash at either side thereof which selectively enter apertures 31 in a guide member 32. If it is desired to rotate the window, the bolts 30 are drawn inwardly and thereupon the sash is swung 30 about its pivots 15 which in the lower position extend into the openings 23.

The upper window sash 11 is also provided with brackets 33 having projections 34 which are guided in slots 35 in the window frame 10. As 35 shown in Fig. 4 chains or cords 36 and 37 respectively are secured to the projections 34 and 15 15 and are trained around pulleys or sheaves 38 and 39, respectively, to be secured to the usual sash weights 40.

The upper sash 11 is guided and held in alignment by a flange 41 of a vertical member 42 and an additional guide member 43 mounted intermediate the sashes 11 and 12. The member 43 terminates as at 44 and a similar member 45 45 is secured to either side of the sash.

Mounted on the frame 10 is a bearing member 46 (Figs. 2, 6) provided with an opening 47 extending into a slot 48 through which enters the projection 34 of the sash bracket. If it is desired 50 to rotate the upper sash inwardly, the lower sash is first swung inwardly as indicated in Fig. 2. Thereafter the upper sash is lowered until the lug 34 is within the opening 47. In this position the upper edge of the sash 11 has cleared the 55

member 43 and the sash may now be swung inwardly until it assumes a horizontal position.

As will be seen from Fig. 4, the members 42 and 43 serve as weather strips for the upper sash.

The lower sash 12 abuts against weather strips 49 (Fig. 5) which are provided with a channel 50 to receive a wiping member 51 secured to the sash 12.

Attention is called to the fact that blades 28 are spring thrust into closed position by a spring 27 shown in Fig. 2, so that upon swinging the lower sash inwardly the blades are held open and upon return of the sash into vertical position the blades automatically occupy the closed or full line position shown in Fig. 4.

While the drawings show a preferred embodiment of the invention, numerous changes and alterations may be made without departing from the spirit of the invention.

I, therefore, do not limit myself to the details of construction and arrangement as shown, but claim my invention as broadly as the state of the art permits.

I claim:

1. In a window construction, a window frame having vertical members, two sashes fitted between said members and reciprocating to pass each other, bearing members near the bottom of said window frame and secured thereto, and means including resilient sealing members for permitting tilting of said sashes upon reaching a predetermined position relative to said bearing members.

2. In a window construction, a window frame, two sashes reciprocating in said frame to pass each other, bearing members near the bottom of said window frame, and secured thereto, lugs extending from said sashes and permitting tilting thereof upon being received in appertaining bearing members, and resiliently held strips normally urging one of said sashes in vertical position said strips constituting sealing means.

3. In a window construction, a window frame, two sashes reciprocating in said frame to pass

each other, bearing members near the bottom of said window frame and secured thereto, and lugs extending from said sashes, said lug having the sash cords attached thereto and permitting tilting of said sashes upon entering appertaining bearing members, and resiliently held strips normally urging one of said sashes in vertical positions said strips constituting sealing means.

4. In a window construction, a window frame, two sashes reciprocating in said frame to pass each other, and means secured to the bottom of said window frame permitting tilting of said sashes upon the latter occupying a predetermined position relative to said bearing members, and resiliently held strips normally urging one of said sashes in vertical position said strips constituting sealing means.

5. In a window construction, a window frame having vertical members, two sashes fitted between said members and reciprocating to pass each other, means for permitting tilting of said sashes, and strips hingedly connected to said window frame and normally urging one of said sashes in vertical position said strips constituting sealing means.

6. In a window construction, a window frame having vertical members, two sashes fitted between said members and reciprocating to pass each other, means for permitting tilting of said sashes, strips hingedly connected to said window frame and bearing against one of said sashes, and means for normally holding said strips in operative position said strips constituting sealing means.

7. In a window construction, a window frame having vertical members, two sashes fitted between said members and reciprocating to pass each other, means for permitting tilting of said sashes, strips hingedly connected to said window frame and bearing against one of said sashes, and resilient means for normally holding said strips in operative position said strips constituting sealing means.

SPIRO PRIFTI. 45
